UNITED STATES PATENT OFFICE.

JOSEPH RICKETTS, OF KANSAS CITY, MISSOURI.

DESIGN FOR A LAYER-LOOP.

No. 39,961.

Specification for Design.

Patented May 4, 1909.

Application filed February 2, 1909. Serial No. 475,727. Term of patent 7 years.

To all whom it may concern:

Be it known that I, JOSEPH RICKETTS, a citizen of the United States, residing at Kansas City, in the county of Jackson and State of Missouri, have invented a new, original, and ornamental Design for Layer-Loops, of which the following is a specification, reference being had to the accompanying drawing, forming part thereof.

Figure 1 is a perspective view of a layer

loop showing my new design, and, Fig. 2 is an edge elevation thereof.

What I claim is:

The ornamental design for a layer loop as shown.

JOSEPH RICKETTS.
